C. D. RICHARD

ELECTRICAL SWITCHING DEVICE

Filed Nov. 6, 1922

Inventor:
Charles D. Richard.

by W. Beatty, A.T.T.

UNITED STATES PATENT OFFICE.

CHARLES D. RICHARD, OF NEW BRIGHTON, NEW YORK, ASSIGNOR TO WESTERN ELECTRIC COMPANY, INCORPORATED, OF NEW YORK, N. Y., A CORPORATION OF NEW YORK.

ELECTRICAL SWITCHING DEVICE.

Application filed November 6, 1922. Serial No. 599,258.

To all whom it may concern:

Be it known that I, CHARLES D. RICHARD, a citizen of France, residing at New Brighton, in the county of Richmond, State of New York, have invented certain new and useful Improvements in Electrical Switching Devices, of which the following is a full, clear, concise, and exact description.

This invention relates to electrical switching apparatus and more especially to that class of switching apparatus used for the establishment of telephone and similar connections.

The object of the invention is to improve the construction and operation of switching devices by reducing the number of moving parts and by simplifying the function of these parts.

A feature of the invention is the provision of a switch having two sets of contact elements certain ones of which extend through apertures in a pair of actuating members, the cooperation of said members serving to effect connection between the contact sets.

Other advantages contemplated by this invention will be taken up in detail in the following description and also pointed out in the annexed claims.

The invention is an improvement on switch structures of the general type disclosed in Patent No. 1,515,735 granted to Charles L. Goodrum and J. N. Reynolds on November 18, 1924.

In the drawing Figs. 1 and 2 illustrate one modification of a selective switching device, while Figs. 3, 4 and 5 disclose a second modification embodying the principles of this invention. Fig. 1 is a front view illustrating a portion of the switch structure; Fig. 2 is a side view of the same construction taken on the broken line in Fig. 1; Fig. 3 is a front view showing a portion of the structure of the second modification; Fig. 4 is a side view taken along the broken line in Fig. 3; Fig. 5 is a detail on an enlarged scale illustrating the action of the movable contacts as they engage the respective passive contacts.

Considering first the switch disclosed in Figs. 1 and 2, a plurality of contact operating members 1 are provided each of which comprises a longitudinal strip of insulating material. Each member 1 is individual to a vertical row of contact elements and serves

as will be explained hereinafter to prepare these elements for engagement with the co-operating contacts. For each set of contacts controlled by the operating member 1 there occurs in said member a rectangular opening or aperture 3.

Coacting with the members 1 are a plurality of operating members 2 arranged at right angles and constituting a second set. The operating members 2 are likewise made of some suitable insulating material and are each provided at each intersection with an operating member 1 with three L-shaped apertures 7. The apertures 7 are so arranged as to register with the aperture 3 in the corresponding operating member 1.

The operating members 1 of the first set are suitably supported in the frame of the switch (not shown) for movement in a longitudinal direction. Electromagnets 6 are provided with armatures 15 and serve to pull the respective members 1 downwardly to the set position, while retractile springs 16 withdraw said members 1 to their normal positions when magnets 6 become deenergized.

The operating members 2 of the second set are likewise actuated by means of electromagnets 4 and are provided with an armature 26 and a retractile spring 5.

The horizontal operating members 2 are each provided with a number of metallic terminal strips rigidly connected thereto by means of rivets or in any other suitable fashion. In the disclosure three of these strips are shown having integral projecting portions 12, 13, 14, 23, 24 and 25 which form contact elements. The three metallic strips are insulated from each other. As seen best in Fig. 1 the projecting contact portions such as 12, 13 and 14 occur in proximity to the L-shaped apertures in the operating members 2.

The other set of contact elements comprises flexible bare wire conductors such as the conductors 9, 10, 11, 17, 18, 19, 20, 21, and 22. These flexible conductors are secured at one end in insulating blocks 27 and project through the rectangular apertures 3 in the operating members 1 and thence through the L-shaped apertures in the corresponding operating members 2. A guide for the flexible wire conductors is provided in the form of an insulating plate 54. The

plate 54, which may be rigidly secured to the frame, is provided with vertical elongated slots 8 through which the flexible contact elements project. When in their normal position the flexible contact elements extend through the L-shaped apertures in the members 2 to a position where they are enabled to make engagement with the rigid contact portions on said members 2. The normal position of the several parts of the switch is best shown in the upper portion of Fig. 1. Here the flexible wire contacts 9, 10 and 11, for example, rest in the upper portion of the respective L-shaped apertures 7 out of engagement with the rigid contacts 12, 13 and 14.

When it is desired to operate the switch to move any set of flexible contacts into engagement with the corresponding set of rigid contacts, the proper one of the vertical operating members 1 is drawn downwardly by the energization of its magnet 6. The downward movement of the bar 1 causes the upper side of the rectangular aperture 3 to flex the corresponding contact wires 9, 10 and 11 downward. These wires pass down to the bottom of the L-shaped notches where they are in alignment with the respective rigid contacts 12, 13, and 14. Next the proper horizontal operating member 2 is moved to the right in Fig. 1 by the energization of its electromagnet 4. The movement of the member 2 carries the rigid contacts into engagement with the positioned flexible contacts and the connection is effected. The flexible contacts 17, 18 and 19, for example, are shown to be in engagement with the rigid contacts 23, 24 and 25.

It will be noted that during the movement of an operating member 2 that only the particular set of flexible contacts which have been previously positioned by one of the operating members 1 is engaged by the corresponding rigid contacts carried on said member 2. None of the unflexed contacts are disturbed by the moving operating member 2 due to the wide portion of the L-shaped apertures. The relative position of the flexible contacts in the L-shaped apertures after the operating member 2 has been fully advanced is seen in the lower part of Fig. 1. The flexible contacts 20, 21 and 22, for example, which were not flexed downwardly are seen to reside near the left-hand edge of the L-shaped openings 7 with the bar 2 in its advanced position.

By first positioning any two of the operating members 1 and then advancing one of the members 2, the sets of contacts in the two vertical rows may be interconnected through the medium of the contacts on the operated member 2. In this case the contact strips on the operating members 2 serve as links to interconnect the different pairs of flexible wire contacts.

It will be noted that any operating member 1 when moved downwardly positions all flexible contacts under its control. As soon as the desired set of flexible contacts are connected to the corresponding rigid contacts, the operating member 1 may be released, returning all remaining sets of flexible contacts to their normal positions. In Fig. 1 the flexible contacts 9, 10 and 11, which were moved downwardly by the member 1 at the time contacts 17, 18 and 19 were placed in engagement with the rigid contacts 23, 24 and 25, have been released and now reside in their normal positions as seen in the figure. When the operating member 1 has released following the operation of a member 2, the engaged flexible contacts 17, 18 and 19 are prevented from returning and are held in engagement with the rigid contacts due to the pressure exerted by these rigid contacts 23, 24 and 25 and the angle at which they are disposed.

In order to release the connection it is only necessary to deenergize the operating magnet 4 permitting the operating member 2 to return to its normal position and the flexible contacts 17, 18 and 19 spring back into their normal positions.

Should another operating member 1 be subsequently moved downwardly during the advanced position of an operating member 2 the flexible contact elements relating to the member 2 will not engage their cooperating rigid contact members due to the shape of the apertures 7. Observing the flexible conductors 20, 21, and 22, if the member 1 were moved downwardly, these flexible contacts would strike against the edge of the L-shaped apertures 7 before they had reached the contacts 35, 36 and 37.

The modification illustrated in Figs. 3, 4 and 5 will next be described. This switch, is in general the same as the one illustrated in Figs. 1 and 2 and comprises a plurality of operating members 28 arranged to slide up and down in the frame plates 52 and 53. Each member 28 consists of a strip of insulating material and is held in its normal position by means of a retractile spring 58. The strip 28 is operated by an individual electromagnet 47 whose armature 49 is arranged to draw the strip 28 downwardly against the tension of spring 58.

Cooperating with the strips 28 is a second set of insulating strips or operating members, two of which 29 and 30, are shown in the drawings. The strips of the second set are arranged at right angles to the members 28 and are actuated longitudinally by means of individual electromagnets 31 and 32. The operating members 29 and 30 are restored to their normal positions by the retractile springs 33 and 34.

At the point of intersection of an operating member 28 with each of the horizontal

operating strips 29, 30, etc., the member 28 is provided with a rectangular opening similar to that shown in the member 1. Adjacent to the rectangular opening in the member 28, the intersecting operating member 29 is provided with three L-shaped apertures 35, 36 and 37. Similarly, the operating member 30 and all other operating members are provided with these L-shaped openings which register with the rectangular apertures in the operating members of the other set.

The flexible or active contacts of the switch comprise flat contact elements or springs 38, 39, 40, 44, 45, 46, etc. These contact elements are secured to the insulating block 48 and extend through the rectangular openings in the operating strips 28 and thence through the L-shaped openings in the horizontal strips 29, 30, etc.

20 The passive or stationary contact elements of the switch consist of a number of ordinary bare wire conductors 41, 42 and 43, there being a set of these conductors for each of the operating members 28 and arranged for engagement with each set of conductors controlled by an operating member 29, 30, etc. The passive contact wires are attached to the frame of the switch as best seen in Fig. 4. They are secured to the bottom plate 53 and insulated therefrom and then passed through insulating bushings in the top plate 52. After passing through the top plate 52, the wire conductors are secured to a member 50 which is urged upwardly by the coil spring 51 to maintain the conductors under tension.

25 The flexible or active contact elements after projecting through the operating strips of both sets extend to a point where they operate with the respective passive wires as shown in Fig. 4. These active contact strips are each made of a piece of flat conducting material which is twisted at an intermediate point through an angle of substantially 90° and then the outward end of the conductor is fashioned to present a curved or cylindrical surface for engagement with the passive wires. The shape of the free ends of the active contact elements is best illustrated 30 in Fig. 5 where the element 38 is shown in an enlarged scale.

To operate the switch, one of the electromagnets 47 is energized to pull downwardly its operating member 28 against the tension of spring 58. As the member 28 is moved 35 the upper edges of the rectangular slots therein encounter the flexible contact springs 38, 39, 40, 44, 45, 46, etc. and bend them downwardly. The free ends of each set of flexible contacts controlled by the operated member 28 are moved to the bottom of the respective L-shaped openings in the operating members 29, 30, etc.

65 Next, one of the operating members of the other set, such as the member 30, is

moved to the right by the energization of its operating magnet 32. The movement of the member 30 causes the lower left-hand edges of the L-shaped openings to engage and move the respective flexible contacts 44, 45 and 46 into engagement with the passive contact wires 41, 42 and 43. Following the operation of the member 30 the operating member 28 may be released permitting the remaining flexible contacts controlled thereby to be restored to their normal positions. The actuated contacts 44, 45 and 46, however, are held in their operated position due to the pressure exerted by the operated member 30.

The engagement of the flexible contact wires with the rigid contact wires is accompanied by a rolling action of the former in order to clean them to insure good electrical contacts. This action is best illustrated in Fig. 5. Assume that the member 28 is drawn downwardly. This serves to move the flexible contact 38 from its normal position as shown in full lines to its prepared position shown in dotted lines directly below. Next the operating member 29 is moved to the right. The L-shaped opening 35 acts upon the positioned contact spring 38 and carries it along with the member 29 until the forward edge of the spring 38 encounters the stationary wire terminal 41. Further movement of the member 29 causes the flexible contact 38 to twist whereby the curved surface of the free end thereof rolls on the stationary wire 41 until it acquires the position shown in dotted lines at the right.

In order to release the connection it is only necessary to deenergize the magnet 32 allowing the operating member 30 to move back to its normal position. As soon as the member 30 releases its pressure on the actuated contact springs 44, 45 and 46 they unflex and move back into their normal positions.

What is claimed is:

1. The combination in a switching device of two sets of contact elements, a pair of operating members each having apertures through which certain of said contacts normally extend, and means for moving said members, said members cooperating with each other to effect engagement between said sets of contacts.

2. The combination in a switching device of sets of contact elements, a pair of operating members having apertures therein, other sets of contact elements each element of which extends through the apertures in both operating members, and means for moving said members to effect engagement between the first and second mentioned sets of contact elements.

3. The combination in a switching device of a set of contacts, a pair of insulating

strips having apertures therein, a second set of contacts each contact of said second set projecting through the apertures in both of said insulating strips, and electromagnets 5 for moving said strips lengthwise to effect engagement between said first and said second sets of contacts.

4. The combination in a switching device of a set of rigid contacts, a pair of operating 10 members having apertures therein, a set of flexible contacts projecting through the apertures in both operating members, means for moving one member to flex the flexible contacts, and means for moving the other 15 member to effect engagement between the flexible and rigid contacts.

5. The combination in a switching device of a set of contact elements, a pair of operating members having apertures therein, a 20 second set of contacts each contact of said second set extending through the apertures in both operating members, and means for moving said members, said members cooperating due to the shape of said apertures to 25 effect engagement between the contacts of said sets.

6. The combination in a switching device of primary contacts, two sets of operating members having apertures therein, secondary 30 contacts each extending through an aperture in a member of each set, and means for moving any member of one set and any member of the other set to effect engage-

ment between the primary and secondary contacts.

7. The combination in a switching device of primary contacts, two sets of operating members arranged at right angles to each other and having apertures therein, secondary contacts each extending through an 40 aperture in an operating member of each set, and means for moving said members longitudinally to effect an engagement between the primary and secondary contacts.

8. In a switching device, a plurality of primary contacts, two sets of operating members having openings therein, secondary contacts each extending through an opening in a member of each set, means for moving any member in one set to select certain secondary contacts, and means for moving any member in the other set to effect engagement between the selected secondary contacts and certain primary contacts.

9. In a switching device, a plurality of passive contacts, two sets of operating members having openings therein, active contacts each projecting through an opening in a member of each set, and means for moving any member in one set and any member in the other set to selectively engage the active and passive contacts.

In witness whereof, I hereunto subscribe my name this 3rd day of November A. D. 1922.

CHARLES D. RICHARD.
